UNITED STATES PATENT OFFICE.

ADELARD J. CARRIÈRE, OF PUTNAM, CONNECTICUT.

AUTOMOBILE-RADIATOR.

1,090,623.

Specification of Letters Patent. Patented Mar. 10, 1914.

Application filed February 1, 1913. Serial No. 745,652.

To all whom it may concern:

Be it known that I, ADELARD J. CARRIÈRE, a citizen of the United States, residing at Putnam, in the county of Windham and State of Connecticut, have invented new and useful Improvements in Automobile-Radiators, of which the following is a specification.

The purpose of the invention is the provision of a radiator for internal combustion engines which will present a maximum cooling surface and at the same time involve a construction whereby the various parts are readily accessible for repairs, which are frequently made necessary because of the strain to which devices of this character are subjected when in use.

The invention provides a radiator for automobile engines of the internal combustion type, said radiator embodying a body portion and a jacket, the latter being removable to admit of any part of the radiator being reached for needed repair, and such jacket when in position giving a finished appearance to the radiator.

The invention consists of the novel features, details of construction and combination of parts, which hereinafter will be more particularly set forth, illustrated in the accompanying drawing, and pointed out in the appended claim.

Referring to the drawing, forming a part of the specification, Figure 1 is a front view of a radiator embodying the invention, a portion of the jacket being broken away and the dotted lines showing the jacket partly withdrawn. Fig. 2 is a horizontal section of the radiator on the line 2--2 of Fig. 1. Fig. 3 is a vertical cross section on the line 3--3 of Fig. 1.

Corresponding and like parts are referred to in the following description, and indicated in all the views of the drawing, by the same reference characters.

The main or body portion of the radiator comprises an upper header 1, a lower header 2 and cooling tubes 3 which have their ends secured to the opposing sides of the headers. The upper header 1 has its end portions deflected in an outward and downward direction, giving thereto the approximate form of an arch. The lower header 2 is straight. The cooling tubes 3 may be of any construction best adapted to serve the purpose and are provided in longitudinal and transverse

series. There may be any number of longitudinal and transverse lines of tubes and the latter may have their ends secured to the opposing sides of the headers in any manner which will admit of ready replacement when required. The usual inlet and outlet couplings are connected with the headers 1 and 2 to admit of the pipes leading from the jacket of the engine cylinder making connection therewith. The upper header 1 is provided upon its top side with the usual filling tube 4. A plate 5 is arranged at a point between the upper and lower headers and is formed with openings to receive the various cooling tubes. This plate is upwardly bowed between its ends and constitutes a brace for maintaining the cooling tubes in spaced relation and to materially stay and strengthen the same.

The jacket 6 is of a shape to conform to the general outline of the body portion of the radiator and is closed upon all sides except the back and bottom, which latter is open to admit of slipping the jacket upon the body or main portion of the radiator by a downward movement. The front wall of the jacket 6 is formed with a plurality of openings to admit of air passing freely therethrough so as to carry off the heat radiated by the cooling tubes 3. This wall has a marginal portion which is imperforate so as to present a finish as well as to stiffen the jacket at its outer edge. A tube is provided upon the top portion of the jacket at a central point in position to receive the filling tube 4. The tube 7 may serve as a handle for lifting the jacket when it is required to slip the same from the body of the radiator. When the jacket is in position it may be prevented from vertical movement by means of the cap 8 which is screwed or otherwise secured to the upper end of the filling tube 4. The exterior of the jacket may be finished in any manner to present an attractive appearance. The jacket forms a protector for the radiator in addition to producing the desired effect and finish and also serves to hide or cover any marred place in the body of the radiator resulting from repairs or other cause.

A radiator constructed in accordance with this invention is capable of being easily and quickly repaired, since removal of the jacket discloses the vital parts of the body which are readily accessible. The jacket is re-

moved and placed in position by a vertical movement, hence the weight is utilized as means for retaining the jacket in place. Inasmuch as the body portion of the radiator is covered by the jacket it is not incumbent upon the person making the repairs to consume time in making a neat finish. Moreover, should it become necessary to cut one or more of the cooling tubes the same may be spliced without detracting from the appearance of the radiator because such repairs are concealed by the jacket when the latter is in place.

From the foregoing description, taken in connection with the accompanying drawing, the advantages of the construction and the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as

are within the scope of the claim appended hereto.

Having thus described the invention what is claimed as new, is:—

An automobile radiator comprising upper and lower headers and intermediate tubes, the upper header having a centrally disposed filling tube at its top, a jacket detachably fitted to the radiator by a vertically sliding movement, said jacket having its front portion opposite the tubular part of the radiator perforated and said jacket being further provided at its top with a tube to slip over the filling tube of the radiator to form a handle and also serve as means to retain the jacket in position and a cap threaded upon the filling tube and engaging the tube of the jacket to prevent the jacket from moving vertically.

In testimony whereof I affix my signature in presence of two witnesses.

ADELARD J. CARRIERE.
